UNITED STATES PATENT OFFICE.

EUGÈNE SCHNEIDER, OF LE CREUZOT, FRANCE, ASSIGNOR TO SCHNEIDER & CIE., OF PARIS, FRANCE, A LIMITED JOINT STOCK COMPANY OF FRANCE.

WHEELED GUN-CARRIAGE.

1,310,889.

Specification of Letters Patent. Patented July 22, 1919.

Application filed February 14, 1918. Serial No. 217,192.

To all whom it may concern:

Be it known that I, EUGÈNE SCHNEIDER, a citizen of the French Republic, and a resident of Le Creuzot, Saône-et-Loire, France, have invented a new and useful Improvement in Wheeled Gun-Carriages, which invention is fully set forth in the following specification.

This invention has for its object an improved wheeled gun-carriage.

The improved wheeled gun-carriage of this invention is characterized by the feature that the trail head or head of the under-carriage is made in one piece with, or is mounted on two vertical axle pins, each constituting a pivot for a bearing block in which is mounted a wheeled axle capable of oscillating in the vertical plane of the axle. The two combined wheeled axles thus constitute for the gun-carriage a front support which will readily adapt itself to all inequalities of the ground, both during transport and during firing.

An embodiment of this invention is illustrated by way of example in the accompanying drawings, in which:

Figure 1, is a side elevation partly in vertical section showing the gun-carriage in position for transport.

Fig. 2, is a corresponding plan, after removal of the gun barrel and the cradle.

Fig. 3, is a vertical cross-section on the line III—III of Fig. 2.

Figs. 4 and 5, are respectively a side elevation and a plan of the improved gun-carriage in the firing position, and arranged so as to allow of training the gun by horizontal rotation about the trail spade.

Fig. 6 is a diagrammatic partial plan showing one position of the gun-carriage when making a turn during transport.

As shown, each of the side members A of the trail terminates at its forward end in an arm B, fixed to a vertical axle pin C.

Each of these axle pins forms a pivot for a bearing block D, which supports in its turn the pivot pin E for the oscillation of a wheeled axle G—F—G. The sleeve d of each of the bearing blocks D should be retained on its pivot pin C by means of a screwed stud H of which the head may be engaged in a varying step I.

The free oscillation of the wheeled axles about the axle pins E allows, as shown in

Fig. 3, of providing the gun-carriage with a forward support that will readily adapt itself to all the inequalities of the ground. Further, the gun-carriage may be transported, as shown in Figs. 1 and 2, where the trail is shown mounted at its tail on a rear wheel axle J—K—J, while the oscillating wheeled axles G—F—G constitute the elements of a tractor fore-carriage. The tractor fore-carriage may be completed as follows:

On a part d^1 of polygonal section of the bearing sleeve d of each of the oscillating wheeled axles, there is mounted one end of a connecting rod L, the other end of which may be pivoted to a swing-tree M for transport. Fig. 6 shows in plan the relative positions of the swing-tree and the fore-carriage in a turning movement.

The improved gun-carriage may be brought into firing position in such a manner that the training movements of the gun may be effected by rotating the gun-carriage horizontally about its trail spade as a pivot. For this purpose the wheeled axles may be coupled by means of connecting rods whose length is such that when connected together at their free ends L^1 (Figs. 4 and 5) they will lock the bearing blocks D of the oscillating wheeled axle, and then the angle enclosed between the said bearing blocks will be the exact angle that will allow the axles F to oscillate in planes that intersect each other in the geometric axis of the pivot pin N provided on the anchor plate O. In these circumstances the gun-carriage can be rotated horizontally around the pivot N, while rolling over the ground by means of the wheels G of the oscillating wheeled axles.

If desired, the coupling of the wheeled axles for bringing the gun-carriage into firing position may be effected by means of connecting rods other than the connecting rods L. These auxiliary connecting rods may be attached to the bearing blocks D in the prolongation of the connecting rods L, as indicated in dot and dash lines in Fig. 2.

The trail A of the gun-carriage may carry a cradle P, mounted as shown in Figs. 1 and 2, or mounted so as to rotate horizontally in the usual manner. The training movement of the gun-carriage by horizontal rotation of the pivot pin N of the anchorage may be produced by any other suitable means such

as wheel gearing for turning the axle wheels, or by traction exerted upon the connecting rods L, etc.

What I claim is:

- 5 1. In a wheeled gun-carriage, a trail having forwardly extending gun-supporting members, a wheeled axle for supporting the forward end of each of said members, a bearing block for each axle having a pivotal support on and normal to said axle and constituting a bearing support for the forward end of a gun-supporting member, and means for coupling said blocks together whereby said axles may adapt themselves to inequalities of the ground during transport and during firing.
- 10 2. In a wheeled gun-carriage, a trail having forwardly extending gun-supporting members, a wheeled axle for supporting the forward end of each of said members, a bearing block for each axle having a pivotal support on and normal to said axle and constituting a bearing support for the forward end of a gun-supporting member, two connecting rods each connected at one end to a bearing block, and means connecting the free ends of said rods to position said axles in planes intersecting in a point in the longitudinal axis of said gun-supporting trail whereby said wheeled gun-supports may be trained around the end of the trail as a center.
- 15 3. In a wheeled gun-carriage, a trail having forwardly extending gun-supporting members, a wheeled axle for supporting the forward end of each of said members, a bearing block for each axle having a pivotal support on and normal to said axle and constituting a bearing support for the forward end of a gun-supporting member, two connecting rods each connected at one end to a bearing block, and a swing-tree connected to

the opposite ends of said rods whereby said axles may adapt themselves to inequalities of the ground during transport and during firing.

- 30 3. In a wheeled gun-carriage, a trail having forwardly extending gun-supporting members, a wheeled axle for supporting the forward end of each of said members, a bearing block for each axle having a pivotal support on and normal to said axle and constituting a bearing support for the forward end of a gun-supporting member, two connecting rods each connected at one end to a bearing block, and means connecting the free ends of said rods to position said axles in planes intersecting in a point in the longitudinal axis of said gun-supporting trail whereby said wheeled gun-supports may be trained around the end of the trail as a center.
- 35 4. In testimony whereof I have signed this specification.

EUGÈNE SCHNEIDER.
